DRUM CONTAINER

Herbert R. Bliss and Howard G. Allen, Niagara Falls, N. Y., assignors, by mesne assignments, to Boston Wire Stitcher Company, Warwick, R. I., a corporation of Maine

Application May 25, 1932, Serial No. 613,470

3 Claims. (Cl. 229—5.7)

This invention relates to containers which may be either cylindrical in shape or frusto-conical in shape, and which may for convenience be termed "drum containers". The invention is concerned particularly with the provision of such containers constructed primarily of fiber board or the like.

The objects of the invention include, principally, the provision of a novel head or end structure for closing the ends of the container. Such end structure may comprise one or more disks of fiber board or the like, and for the purpose of fastening the end heads to the container walls a new structure is employed which 10 comprises a securing ring. In accordance with the invention this ring preferably has such proportions in cross-section as to provide for securing the same to the circular walls of the container, or, in accordance with variations of the invention, to a circular closure ring and also as well for securing the same to the end head. Thus, the ring constitutes a connecting element. The end head ring may advantageously be formed of fibrous material, as for example, by winding fibrous material such as paper, tightly into shape with the plies of paper or the like being glued or otherwise secured together so that when completed and dry a solid ring structure is provided. The invention will be better appreciated as the detailed description progresses.

In the accompanying drawing:

Fig. 1 is a view of a container of frusto-conical shape illustrating another form of closure head with some of the parts being shown in section.

Fig. 2 is a view of a container illustrating a still further modified form and also showing some of the parts in section.

Fig. 3 is a sectional view taken substantially on line 3—3 of Fig. 2.

Fig. 4 is an enlarged detail illustrating one formation of the ring structure.

Fig. 5 is a detail view illustrating a lap joint.

Fig. 6 is an enlarged sectional view illustrating a form of butt edge seam.

The particular container of Fig. 1 is shown in the form of a bucket or of frusto-conical shape although the head structure may be employed with cylindrical containers. The body of the container may be formed of a blank, as at 20, provided with a suitable seam 21. The head structure may comprise a ring 22 having a disk 23 on its underside, and a cover disk 24 advantageously of a diameter so as to overlap the top edges of the container blank, and the three elements may be united by stitches 25. A reinforcing disk 26

may be used if desired. This cover is advantageously secured to the container by stitches 15.

Another type of container is shown in Fig. 2 wherein the container body 30 is cylindrical, made of a blank with its edges in a seam 31, and due to the type of head structure the seam at 31 preferably has an inside sealing strip 32 held by stitches 3 (Fig. 3) to form a smooth outside surface. The head structure comprises a ring 33 and a sealing disk 34 connected to the ring by 10 stitches 35. This form of the invention has a protector section advantageously of a short cylindrical portion, as shown at 36, fitting over the outside of the container and which may be secured to the ring by stitches 37. The stitches 37, 15 as shown, are of the clinched leg type but they may be of deflected leg type. The bottom of the container shown in Fig. 2 may be of any suitable structure as the bottom need not necessarily be made like the top. This container may be sealed 20 by a gummed strip.

The rings 22 and 33 may be made up by tightly winding fibrous material into a multiplicity of superimposed layers to a substantially predetermined diameter, and the windings may be in the 25 form of a relatively long cylinder. The rings are thus continuous or unbroken as distinguished from split rings. However, these ring structures may be constructed of material other than windings of fibrous material, such as paper, as above 30 described. The rings may be formed of molded pulp and may be used with or without stiffening agents, such as molten sulphur, synthetic resins, or the like. Also the rings may be of molded vulcanized fiber.

Where the rings are made up of superimposed windings it is preferable that the stitches, such as stitches 25, be disposed at an angle to a radial line as illustrated in Fig. 4, so that the legs of each stitch pass through the ring between or adjacent different superimposed windings to minimize the tendency of splitting the ring. The stitches 25, as shown in Fig. 1, may be clinched 35 on the underside of the disc 23.

With the use of such a ring stitches may be 45 used which are not driven completely through the ring but which are embedded therein. Stitches of this type are shown in Figs. 1 and 4. In reference to Fig. 4, it will be noted that the legs of the stitches 15 are angularly disposed, and these 50 stitches are advantageously termed "deflected leg stitches". These stitches may be driven through the material of the wall of the container and into the ring, and the legs are deflected out of a straight path as they are driven, so as to form a 55

sort of tie structure for effectively holding the stitches in place. The formation of such stitches and machine for driving and deflecting the legs thereof are shown in our Patent No. 1,958,739 of May 15, 1934, and further detailed description thereof is not deemed necessary.

The present container of fiber board may be employed for many different articles of merchandise, as for example, soap powder, lime, chemicals, meat products, soap flakes, wire in coils, rolls of screen cloth, textile goods, or semi-solid stuffs like lard, butter or cheese. In containers, from which portions may be dispensed from time to time, the head structure as shown in Fig. 1 may be employed as the stitches 15 may be removed and then the head may be easily removed and replaced. The type of structure shown in Fig. 2 is advantageous for use in shipment of cheese or the like.

The container is one which may be shipped to the user in flat form, the body blanks being flat, and the head structures may be completed by the manufacturer so that all that the user has to do is shape the body blank and finish its seam and then fasten the end heads thereto. It is within the invention to make the body of the container from more than one blank.

It is to be understood that the containers shown herein, and other containers which may fall within the claims, may be used with any sort of seam or joint, as for example, the lap joint as illustrated in Fig. 5. This is a simple type of seam; the edges of the material 20 may be overlapped as shown and secured together advantageously by penetrating devices such as stitches 3. A stronger type of butt seam is illustrated in Fig. 6. Here the strip 2 is attached to the ends or edges of the material 20 by two rows of stitches 3a and 3b, the stitches 3a penetrating one edge of the material 20, and the stitches 3b penetrating the other edge.

We claim:—

1. In a fiber board container, a drum-shaped container body of fiber board, an end head comprising a disk of fiber board having dimensions such as to rest upon the edge of the fiber board material of the body, a fibrous ring on the inside of the end head fitting relatively snugly against the inside peripheral walls of the body, metallic penetrating means extending through the end head and ring, and metallic penetrating means driven through the body blank and embedded in the ring. 5

2. In a fiber board container, a drum-shaped container body of fiber board, an end head comprising a disk of fiber board having dimensions such as to rest upon the edge of the fiber board material of the body, a fibrous ring on the inside of the end head fitting relatively snugly against the inside peripheral walls of the body, metallic penetrating means extending through the end head and into the ring, and U-shaped stitches embedded in the ring and extending through the material of the body with the legs of the stitches being disposed substantially out of parallelism whereby to tie into the material of the fiber ring. 10

3. A drum type container of fiber board comprising a drum-shaped container of fiber board, a fibrous ring fitted within one end of the container having cross-sectional dimensions such as to receive axially disposed stitches and radially disposed stitches, a fibrous disk inside the ring, a fibrous disk outside the ring with its edges lapping over the edge of the container body, metallic devices penetrating in an axial direction through the fibrous ring and into end head disks, and other metallic penetrating devices extending in a radial direction through the container wall and into the fibrous disk. 15
